Ralph M. Vigna, Rochester, N.Y., assignor to Eastman
Kodak Company, Rochester, N.Y., a corporation of
New Jersey

Filed Jan. 17, 1968, Ser. No. 10,193

Term of patent 14 years

Int. Cl. D16—05

U.S. Cl. D61—1

FIG. 2

FIG. 3

FIG. 4

FIG. 1 is a front perspective view of a photographic processing apparatus showing my new design;

FIG. 2 is a rear perspective view showing the other sides thereof;

FIG. 3 is a bottom plan view thereof; and

FIG. 4 is a front perspective view similar to FIG. 1, but wherein the drum and its support have moved (i.e., tilted forward) to another position.

The broken line showing in FIGS. 1, 2 and 4 a drum or similar article, with which the support structure of my novel design may be associated, is for illustrative purposes only.

I claim:

The ornamental design for a photographic processing apparatus, as shown and described.
